UNITED STATES PATENT OFFICE.

FRANK DE MINICO, OF NEW YORK, N. Y., ASSIGNOR TO POLLARD-ALLING MANUFACTURING COMPANY, OF NEW YORK, N. Y., A CORPORATION OF NEW YORK.

ADDRESSING MACHINE.

Application filed March 17, 1923. Serial No. 625,684.

To all whom it may concern.

Be it known that I, FRANK DE MINICO, a citizen of the United States, and a resident of New York, borough of Bronx, in the county of Bronx and State of New York, have invented certain new and useful Improvements in Addressing Machines, of which the following is a specification.

This invention relates to addressing machines and has for its object to provide means, in a machine of the class specified, for printing on certain selected articles addresses, a character to indicate certain classifications of said articles, such, for instance, as town classification.

With these ends in view and others which will appear later herein, my improvements comprise features illustrated in their preferred embodiment in the drawings accompanying this specification, wherein:

Figure 1 is a side elevation with the front frame of the machine omitted. Fig. 2 is a plan view corresponding with Fig. 1. Fig. 3 is a fragmentary side elevation, partly in section on line 3, 3 of Fig. 2, similar to a portion of what is shown in Fig. 1, and illustrates a step in the operation of the machine. Figs. 4 and 5 are fragmentary side elevations of portions of what is shown in Figs. 1 and 3 and illustrate steps in the operation of my improved machine. Fig. 6 is a fragmentary bottom plan view corresponding with Fig. 5. Figs. 1 to 3 inclusive are to one scale, while Figs. 4 to 6 inclusive are to a common larger scale.

My present invention is in the nature of improvements in the machine set forth in my copending application for addressing machines, Serial Number 394,517 filed July 7, 1920, and to which reference may be had. The present improvements are particularly directed to the simplification of the mechanism of the machine of that application.

The machine set forth herein is particularly adapted for printing on the margin of an article, such as a newspaper, the address of the person for whom the article is intended, from one of a series of plates having that address embossed thereon, and which series of plates are hinged together into a chain of plates, and said chain and papers are fed through the machine in coacting relation. In Figs. 1 and 2 a chain of address plates 2 comprising a plurality of individual, articulated plates, as 4, each having

on its outer face a suitable embossed address, not shown, but of a character well-known in the art, is advanced so as to present each successive plate to printing position by means of drum 5 fixed to shaft 6. 60 This drum is rotated continuously through reduction gearing from shaft 8 and which shaft makes one complete rotation for each incremental advance of drum 5. Said plates 4 may be inked by means of some suitable inking device, known in the art but not shown. Below said drum, for supporting the articles to be printed, are rails 9 and said articles, as N, are advanced from left to right over said rails by means of intermittently coacting pairs of feed rolls, as lower rolls 10, 10 fixed to shaft 8, and upper rolls 11, 11 mounted for free rotation on the free ends, respectively, of bell cranks 12, 12 turning freely on fixed shaft 13. Said rolls 70 75 are spaced apart on their respective shafts so as to engage the articles at remote portions transversely thereof. Upper rolls 11, 11 are normally urged to coaction with their respective lower rolls 10, 10 by pull springs, 80 as 14, connecting the upper arms, as 15, of said bell cranks with arms, as 16, adjustably fixed to shaft 13. Other similar pairs of coacting rolls 17, 17 below, fixed to shaft 18, and 19, 19 above, carried by bell cranks 85 20, 20, turning freely on fixed shaft 21, are provided for advancing the articles over rails 9 after the earlier sets of rolls have performed their functions.

Roll 22 above carried by bell crank 23 90 turning freely on sleeve 37 of fixed shaft 24, coacts with roll 25 below fixed to shaft 26 for delivering the printed article from the machine. Roll 22 is urged to constant coaction with roll 25 by pull spring 27 which 95 connects the upper arm of bell crank 23 with arm 28 adjustably fixed to shaft 21. Rolls 11, 11, and 19, 19 are lifted intermittently in unison from coaction with their respective lower rolls by means of eccentrics, as 29, the strap 30 of which has rod 31 extending to the right therefrom and which rod extends through suitable openings in the upstanding arms of bell cranks 12 and 20 and is provided with adjustable 100 nuts 32, 33, respectively, for engaging said arms. Said eccentrics, as 29, are fixed to main shaft 70.

Fixed to sleeve 37 and downreaching therefrom are stop fingers 34, 34 the opera- 110

tive ends of which are adapted to be thrust into the path of the articles N as those articles are advanced through the machine. These fingers are lifted from time to time 5 as required by eccentric 35, the strap 36 of which is connected by rod 38 with upstanding arm 39 fixed to sleeve 37. Said eccentric 35 also is fixed to shaft 70.

Directing attention now to the means for 10 printing on certain articles N selected for distinction, printer 40, preferably in the form of a disc of felt or the like, is carried by bell crank 41 mounted for oscillation on stud 42 projecting from frame plate 43. 15 Said plate is supported on fixed shafts 21, 24. Said printer 40 is preferably backed by ink supply case 44. The upstanding arm of bell crank 41 is in the nature of a cam arm and is preferably provided with anti- 20 friction shoe 45 of hardened steel and said arm is connected by link 46 with feeler arm 47 upstanding from sleeve 48 turning freely on fixed shaft 21. Pull spring 49, one end of which is fixed to link 46 and the other end to plate 43 is efficient for holding printer 40 normally away from the adjacent rail 9 and shoe 45 out of the path of hammer 50, Fig. 3. Pin 58 in plate 43 limits the movement of arm 47 to the right. Down-reaching 30 from sleeve 48 is arm 51 having pivoted in its lower end at 53 feeler finger 52. Said finger preferably comprises two members, body 52^a pivoted at 53 as described and the finger proper 52, reaching to the left under 35 drum 5, a portion of the operative end of said finger being under ratchet 54 which forms a flange or head for one end of said drum. Finger body 52^a has rearwardly reaching to the right, arm 52^b for engagement 40 at certain times in the operation of the machine with pin 55 carried by arm 56 fixed to shaft 21. The operative end of finger 52 is urged upwardly toward drum 5 by pull 45 spring 57. Said operative end of finger 52 comprises feeler 59 adapted for entering one 50 at a time, pockets, as 61, in said chain plates, and pawl 60 adapted for engagement by one of the teeth of ratchet 54 when said feeler enters one of said pockets, see Figs. 55 5 and 6. Those address plates which are adapted for indicating the operation of the selective printer 40 preferably have a square portion cut from a corner thereof, as at 61, in plates 4^a, 4^b, best shown in Fig. 6. Drum 5 60 preferably has cavities, as 62, cut in each plate seat at the edge of said drum so that feeler 59 is permitted a sufficient movement into or through plate pocket 61 to insure suitable engagement of pawl 60 by the adjacent tooth of ratchet 54. Hammer 50 is carried by one arm of bell crank 63 pivoted at 64 in plate 43, at the right hand end of Figs. 1, 2 and 3. The other arm of said bell crank is pivoted at 65 to the slotted end of connection 66. The other end of said connection

is fixed to strap 67 of eccentric 68 fixed to shaft 70.

The several shafts are gear driven from main shaft 70 as follows: Equal gears 71, 72 fixed to shafts 70 and 8, respectively, intermesh and through intermediate gear 69 fixed to short shaft 7, gear 72 drives equal gear 73 fixed to shaft 18. Gear 74 fixed to shaft 18, through intermediate gear 75 fixed to short shaft 76, drives equal gear 77 fixed to shaft 26. Bevel gear 78 fixed to shaft 8 drives bevel gear 79 fixed to the lower end of vertical shaft 80, and the upper end of that shaft has fixed thereto worm 81 in engagement with worm gear 82 fixed to shaft 6. It will thus be seen that shafts 70, 8, 18 and 26 rotate at the same speed and feed rolls 10, 10, 17, 17, and 25, being of one diameter have equal surface speeds. Also the timing of shafts 70 and 6 is such that for each rotation of shaft 70, shaft 6 and drum 5 make a fractional rotation equal to one printing plate increment. Also rolls 11, 11, and 19, 19 coact with their respective lower rolls 10, 10, and 17, 17 through about three quarters of each rotation of those lower rolls, during which time of coaction the articles are advanced over rails 9.

The operation of my improved machine is as follows: An article or paper N, to be 95 printed with an address, and in some cases with a further distinguishing mark, is advanced onto rails 9 to position N¹, Fig. 1, by hand or by some automatic feed mechanism of known character, not shown, and during the first cycle of operation of the machine, coacting rolls 10, 10, and 11, 11, respectively, advance the article from said position N¹, Fig. 1, through position N², Fig. 3, to position N³, Fig. 1 against stops 34, 34, which are at that time in the lowered position of Fig. 1. Rolls 11, 11 are then lifted by their eccentrics, as 29, Fig. 1, leaving said article at rest in printing position. Platen 83 is then raised from the position of Fig. 3 to that of Fig. 1, by means not shown but well known in the art, thereby pressing the left hand portion of the article N against the lowermost plate on drum 5, whereby the address on that plate is impressed upon the article. Usually this completes the printing function of the machine and the selective printer 40 remains in the position of Fig. 3 and hammer 50 descends to the left of and without engaging shoe 45, Fig. 3. But if the plate from which the address is printed, as 4, Fig. 6 is the first of a classification series, such as the first address in a given town, then the last address plate 4^a of the preceding classification series, which is just in advance of plate 4, Fig. 6, is provided with cutout 61 for the reception of feeler 59 of finger 52, whereby pawl 60 is permitted to rise into the path of the adjacent tooth 84 of ratchet 54 and which 110

tooth pushes finger 52 to the right from the position of Figs. 3 and 5 to substantially the position of Fig. 1. This rotation of drum 5 brings plate 4, Fig. 6, into printing position and the endwise thrust of finger 52 swings arm 47 in anticlockwise direction and thereby, through link 46, swings bell crank 41 in the same direction, whereby printer 40 descends toward the right hand end of article N, Fig. 1, and shoe 45 swings into the path of descending hammer 50, and which hammer presses printer 40 against the article, thereby printing thereupon, Fig. 1. The descent of hammer 50 onto shoe 45 also swings arms 47, 51 slightly farther than the tooth of ratchet 54, through finger 52, has previously swung those arms, whereby arm 52^b of finger 52 encounters pin 55, which throws finger 52 out of engagement 20 with the ratchet tooth, Fig. 1.

Usually, when the printing plates have no cutout portions 61, feeler 59 rides over the surface of the successive plates, Fig. 4, and fails to admit pawl 60 into engaging relation with the ratchet teeth.

After the printing has been done platen 83 descends and hammer 50 ascends, thereby permitting spring 49 to return printer 40 to its idle position, Fig. 3, and finger 52 to feeling position against the chain of plates on the drum. Also stops 34, 34 are raised and rolls 19, 19 descend into coaction with lower rolls 17, 17, respectively, whereby the printed article is advanced to the right into the grip of rolls 22, 25 and by which rolls it is discharged from the machine. Coincident with the descent of rolls 19, 19, rolls 11, 11 descend and in coaction with lower rolls 10, 10, respectively, advance another article from position N¹ to printing position N², Fig. 1, stops 34, 34 descending just before the article reaches said printing position, to locate the article.

I claim:—

- 45 1. In a machine of the class described the combination of a series of printing plates, a drum for advancing said plates serially to and away from printing position, two pairs of upper and lower coacting feed rolls arranged for successive engagement with the article to be printed, means for bringing an article and a plate into printing engagement, means timed with the printing mechanism for holding said pairs of rolls out of coaction during the operation of said printing mechanism, a stop movable into and out of the path of the article to be printed, and means timed with the printing mechanism for actuating said stop.
- 50 2. In a machine of the class described the combination of a series of printing plates, a drum for advancing said plates serially to and away from printing position, means for advancing articles to be printed to and away from said printing position, means for

bringing an article and a plate into printing engagement, a classification printer mounted on one arm of an oscillatable bell-crank, an oscillatable hammer for operatively engaging the other arm of said bell-crank, and means for moving said other bell-crank arm into and out of the path of said hammer whereby said classification printer is caused to make an impression upon a predetermined article.

3. In a machine of the class described the combination of a series of printing plates, a drum for advancing said plates serially to and away from printing position, means for advancing articles to be printed to and away from said printing position, means for bringing an article and a plate into printing engagement, a classification printer mounted on one arm of an oscillatable bell-crank, an oscillatable hammer for operatively engaging the other arm of said bell-crank, and means for moving said other bell-crank arm into and out of the path of said hammer comprising a feeler finger operatively connected with said other bell-crank arm, a ratchet fixed coaxially with said drum and having a peripheral tooth corresponding with each printing plate on said drum, one of said printing plates having a pocket therein contiguous to a tooth on said ratchet, said feeler finger being adapted for operative engagement with said tooth through said pocket, whereby said classification printer is caused to make an impression upon a predetermined article.

4. In a machine of the class described the combination of a series of printing plates, a drum for advancing said plates serially to and away from printing position, means for advancing articles to be printed to and away from said printing position, means for bringing an article and a plate into printing engagement, a classification printer mounted on one arm of an oscillatable bell-crank, an oscillatable hammer for operatively engaging the other arm of said bell-crank, means for moving said other bell-crank arm into and out of the path of said hammer whereby said classification printer is caused to make an impression upon a predetermined article, a stop movable into and out of the path of the article to be printed, and means timed with the printing mechanism for actuating said stop.

5. In a machine of the class described the combination of a series of printing plates, a drum for advancing said plates serially to and away from printing position, means for advancing articles to be printed to and away from said printing position, means for bringing an article and a plate into printing engagement, a classification printer mounted on one arm of an oscillatable bell-crank, an oscillatable hammer for operatively engaging the other arm of said bell-

crank, means for moving said other bellcrank arm into and out of the path of said hammer comprising a feeler finger operatively connected with said other bellcrank arm, a ratchet fixed coaxially with said drum and having a peripheral tooth corresponding with each printing plate on said drum, one of said printing plates having a pocket therein contiguous to a tooth on said ratchet, said feeler finger being adapted for operative engagement with said tooth

through said pocket, whereby said classification printer is caused to make an impression upon a predetermined article, a stop movable into and out of the path of the article to be printed, and means timed with the printing mechanism for actuating said stop.

In witness whereof, I hereby affix my signature this 16 day of March, 1923.

FRANK DE MINICO.
